UNITED STATES PATENT OFFICE.

BENJAMIN F. AUGUSTINE, OF BUFFALO, NEW YORK.

ROTARY ENGINE.

984,061.

Specification of Letters Patent. Patented Feb. 14, 1911.

Application filed June 6, 1910. Serial No. 565,292.

To all whom it may concern:

Be it known that I, BENJAMIN F. AUGUSTINE, a citizen of the United States, residing at Buffalo, in the county of Erie and State of New York, have invented certain new and useful Improvements in Rotary Engines, of which the following is a specification.

This invention relates to rotary engines.

One object is to provide a freely operating piston capable of reciprocation with a minimum of friction to overcome binding or undue wear between the piston and its carrier.

With the above and other objects in view, the present invention consists in the combination and arrangement of parts herein-after more fully described, illustrated in the accompanying drawings, and pointed out in the appended claims, it being understood that changes may be made in the form, proportion, size and minor details without departing from the spirit or sacrificing any of the advantages of the invention.

In the drawings: Figure 1 is a vertical longitudinal sectional view. Fig. 2 is a vertical transverse sectional view. Fig. 3 is a detail view of the automatically balanced valve. Fig. 4 is a detail view of one of the pistons. Fig. 5 is a detail view of one of the abutments. Fig. 6 is an internal face view of one of the cylinder heads. Fig. 7 is a detail perspective view of the rotary carrier, illustrating my improved bearing applied thereto. Fig. 8 is a face view of one of the cylinder disks. Fig. 9 is a fragmentary face view of a portion of one end of the carrier, partly in section. Fig. 10 is a fragmentary edge view of one end of the carrier.

Referring now more particularly to the accompanying drawings the reference character 1 indicates a cylinder or casing and 2 a power shaft journaled in the cylinder and 45 in suitable adjustable bearings 3 on opposite sides of the cylinder.

Fixedly secured to the shaft 2 is a rotary piston carrier composed of two sections 4 and 5, both arranged to rotate in the casing 50 and to contact on one side thereof. These sections 4 and 5 of the carrier are provided with pistons 6 and 7, respectively, and slideable in radial slots 8 and 9, respectively, in which the pistons reciprocate as the carrier 55 rotates.

In Fig. 4 the piston 7 is shown as pro-

vided on one side with a short arm 10 carrying on its outer end a bushing 11 while on its opposite end the piston is provided with the long arm 12 which carries the bushing 13 at its outer end. The pistons 6 and 7 are formed alike and each has piston rods 14 which carry at their outer ends the counter-weights 15, the character 16 indicating a removable packing strip carried by the 65 piston.

The sections 4 and 5 of the carrier are provided with the interior radial chambers 18 and 19 for the snug sliding reception of the counter-weights 15 on the piston rods 14 of the pistons 6 and 7. The piston rods 14 which connect the counter-weights 15 with the respective pistons 6 and 7 are adapted to pass loosely through the sections 4 and 5 and the shaft 2, as clearly shown in 75 Fig. 1, there being roller bearings 16' between the weights 15 and the chambers 18 and 19.

The characters 20 and 21 indicate outer disks keyed to the shaft 2 and bolted to the 80 sections 4 and 5. These disks 20 and 21 form outer end walls for the radial piston slots 8 and 9 and the radial chambers 18 and 19. Radial slots 22 in the disks 20 and 21 are provided to permit of the passage 85 therethrough of the arms 10 and 12 of the pistons 6 and 7, the long and short arms of one piston being disposed opposite to the short and long arms of the other piston, as clearly shown in Fig. 1.

The characters 23 and 24 indicate the cylinder heads bolted to each end of the casing or cylinder 1.

On the inner faces of the cylinder heads 23 and 24 are the circular channels 28 95 adapted to slidably receive the cross heads 29 secured to the outer ends of the long and short arms of the pistons 6 and 7, there being a hard metal ring 25 removably secured in the channel 25' in the inner face of each 100 head 23 and 24 to prevent undue wear of the heads or the disks 20 and 21.

The character 30 indicates abutments, each of which has its outer cylindrical wall 31 in close contact with the inner cylindrical 105 wall of the casing 1. The inner cylindrical wall 32 of the abutment 30 is eccentric with the sections 4 and 5 of the carrier and the shaft 2. On each side of the abutment 30 is an annular flange 33, forming an annular 110 recess for the reception of the flange 34 on the section 5 and the disk 21 (see Fig. 1).

Between the side walls of the abutments and the side walls or the flanges of the sections 4 and 5 of the carrier, spring pressed metal packing rings 35 are interposed for a purpose well understood.

Within the thicker side of each abutment is a transverse cylindrical chamber 36, in each of which are packing blocks 37 each having a short stem 38. Between corresponding short stems 38 of the packing blocks 37 are interposed spiral springs 39 for pressing the packing blocks against the inner surfaces of the flanges on the sections 4 and 5 of the carrier. By virtue of the pressure of the springs 39 against the ends of the stems 38 of the packing blocks 37 the latter are not liable to tilting action, the springs 39 exerting pressure centrally of said blocks and thereby maintaining them in true relation against the inner surfaces of the flanges of the sections composing the carrier.

Extending through the abutments are the inlets 40 and the exhaust ports 41. Communicating with the exhaust ports 41 is the common exhaust chamber 42 (see Fig. 2) having the outlet pipe 43 leading therefrom.

The character 44 indicates a hollow cylindrical valve adapted to be oscillated within its chamber 45 and it is provided with the outlet ports 46 and 47, out of line with each other sufficiently to overlap the inlet ports 40 of the abutments 30 when the valve is centered. The center portion of the valve 44 is preferably cut away at 48 to form with the surrounding chamber 45 an annular chamber into which the expansive fluid passes through the perforations 49 to effect a proper balance of the valve. The expansive fluid is conveyed into the valve 44 by way of the inlet 50.

The valve 44 has a valve stem 51 which projects through the casing 1 and at the outer end of the valve stem 51 is keyed one end of the rocker arm 52 (see Fig. 1), the outer end of the connecting rod 53, having its upper end rigidly connected with the eccentric strap 54 surrounding the cam 55, forming a part of the centrifugal governor 56, which may be of any well known type.

The operating fluid (either steam or gas) enters through the passage 50 to the valve 44, and passing through the perforations 49, 55 enters the interior of the valve 44 ready for operative action.

When the piston 7 passes the inlet port 50 the outlet port 47 in valve 44 commences to register with the port 40 and is cut off automatically by the action of the centrifugal governor 56, the degree of registration of port 40 with port 47, from full to partial, being automatically regulated through the governor 56, by the varying load. The instant that piston 7 completes

the first half of its stroke the piston 6 in the adjacent section of the rotary carrier crosses the corresponding inlet port 40 and at the next instant outlet port 46 in the valve 44 commences to register with said other exhaust port and is cut off automatically in the same manner as heretofore described in connection with the port 47.

The character 57 indicates an opening in the wall of the cylindrical valve 44 diametrically opposite the outlet port 47 and slightly larger than said port. This opening 57 is to effect a steam tight joint between the upper wall of the valve 44 and the contacting wall of its chamber around the point of junction of the port 47 with the lower end of the inlet port 40. The opening 57 has the same relation to the port 47 as the opening 57' with relation to the port 46 and both are designed to effect and maintain a proper balance of the valve.

It will now be understood that the pistons reciprocate alternately in the radial slots of the carrier, and in order to facilitate and provide for an even and efficient reciprocation of the pistons, I provide each piston at each end with a recess 59 adapted to receive the lug 60 of the socketed member 61 whose opposite ends have lugs 62 to engage over the rear edge of the piston, there being one of these socketed members 61 at each end of each piston with each member provided with spaced sockets 63 adapted to receive the bearing balls 64 in such manner as to permit the balls to engage the bottoms of their sockets and rotate freely therein.

The socketed members 61 co-operate with the guide members 65 secured in the recesses 66 of the flanges 34 of the carrier adjacent the piston slots 8 and 9, the inner ends of the guide members resting upon the shoulders 67 of the carrier and their outer ends being secured to the latter by means of a suitable pin 68. Each guide member has a longitudinal groove 69 in which the bearing balls 64 travel during reciprocation of the pistons. The socketed members 61 are not fastened to the pistons but are locked against lateral play by the balls 64 interposed between them and the guide members irrespective of whether the disks 20 and 21 are disposed against the ends of the carrier.

What is claimed is:

1. In a rotary engine, in combination, a cylinder, a piston carrier journaled in the cylinder and provided with radial slots, the carrier being recessed adjacent one side of each slot, a grooved guide member fitted in each recess, a piston slidable in said slots, the piston having recesses in its outer edge, one at each end thereof, socketed members carried by the piston at the ends thereof, each having a lug engaged in the corresponding recess of the piston and having its opposite end provided with a lug to engage the rear

edge of the piston, and bearing balls carried in the sockets of the socketed members and traveling in the grooves of the guide members.

- 5 2. In a rotary engine, in combination, a cylinder, a piston carrier journaled in the cylinder and provided with radial slots, the carrier being recessed adjacent one side of each slot, a guide member fitted in each 10 recess and provided with a longitudinal groove, a piston slideable in said slots, socket members carried by the piston at the ends thereof, and bearing balls carried in the sockets of the socketed members and traveling in the grooves of the guide members.
3. In a rotary engine, in combination, a cylinder, a piston carrier journaled in the cylinder and provided with slots, the carrier being recessed adjacent one side of each 15 slot, a grooved guide member fitted in each recess, a piston slideable in said slots, socketed members carried by the piston at the ends thereof, each having a lug engaging the piston, and bearing balls carried in the 20 sockets of the socketed members and traveling in the grooves of the guide members.
4. In a rotary engine, in combination, a cylinder, a piston carrier journaled in the cylinder and fitted with radial slots, a guide 25 member secured to the carrier adjacent each slot, socketed members carried by the piston at the ends thereof for coöperation with the guide members, and bearing balls carried in the 30 sockets of the socketed members and bearing against the guide members.

5. In a rotary engine, in combination, a cylinder, a piston carrier journaled in the cylinder and provided with radial slots, a longitudinally grooved guide member secured to the carrier adjacent each slot, bearing carrying members carried by the piston at the ends thereof, and bearing elements carried by said bearing carrying members and engaging the guide members to guide 45 the piston and obviate friction.

6. In a rotary engine, in combination, a cylinder, a piston carrier journaled in the cylinder, grooved guide members secured to the carrier, socketed members carried by 50 the piston for coöperation with the guide members, and bearing balls carried in the sockets of the socketed members and traveling in the grooves of the guide members.

7. In a rotary engine, in combination, a cylinder, a piston carrier journaled in the cylinder, and provided with radial slots, the 55

carrier being recessed adjacent one side of each slot, each recess providing a shoulder at its inner end, a grooved guide member fitted in each recess with its inner end bearing against the corresponding shoulder, a pin passed through the outer end of each guide member and into the carrier to secure the guide member in place, a piston slideable in said slots, the piston having recesses in its outer edge, one at each end thereof, socketed members carried by the piston at the ends thereof, each socketed member having a lug engaged in the corresponding recess of the piston and having its opposite end provided with a lug to engage the rear edge of the piston, and bearing balls carried in the sockets of the socketed members and traveling in the grooves of the guide members.

8. In a rotary engine, in combination, a cylinder, a piston carrier journaled in the cylinder, grooved guide members carried by the carrier, bearing carrying elements carried by the piston, and bearing elements carried by the bearing carrying members and engaging the guide members to lock the bearing carrying members in coöoperative relation with the guide members.

9. In a rotary engine, in combination, a cylinder, an abutment in the cylinder, a piston carrier operable in the cylinder and adapted to contact at one point with the abutment, the abutment having a transverse bore, packing blocks disposed at the ends 90 of said bore and having stems, and a spring in the bore bearing at its ends against the inner free ends of said stems.

10. In a rotary engine, in combination, a cylinder, a piston carrier journaled in the 95 cylinder and provided with a pair of slots, grooved guide members secured to the carrier adjacent the slots, socketed members having lugs engaging the front and rear edges of the piston, and bearing balls carried in the sockets of the socketed members and engaging the guide members and locked by the latter in coöoperative relation with the guide members and immovable with reference to the piston.

In testimony whereof I affix my signature in presence of two witnesses.

BENJAMIN F. AUGUSTINE.
